EDWARD V. WURTS, OF NEWARK, NEW JERSEY, ASSIGNOR TO STEEL UTILITIES,
INCORPORATED, A CORPORATION OF NEW YORK.

DISTANCE-DETERMINING MECHANISM FOR METAL-WORKING MACHINES.

1,349,996.

Specification of Letters Patent. Patented Aug. 17, 1920.

Application filed February 11, 1918. Serial No. 216,660.

To all whom it may concern:

Be it known that I, EDWARD V. WURTS, a citizen of the United States, and a resident of Newark, in the State of New Jersey, have invented certain new and useful Improvements in Distance-Determining Mechanism for Metal-Working Machines, of which the following is a specification.

The invention relates to machines for successively traveling through widely varying distances, and accurately stopping metal beams, plates, and the like, in position to be punched or otherwise operated upon by tool-equipped means. More particularly, the invention relates to improvements in the distance determining mechanism for so traveling and stopping the work, and in certain aspects thereof the present invention is an improvement on the machine shown and described in U. S. Patent No. 1,241,258 issued September 25, 1917, to L. A. Hawthorne.

Objects and advantages of the invention will be set forth in part hereinafter, and in part will be obvious herefrom, or may be learned by practice with the invention.

The invention consists in the novel parts, constructions, arrangements, combinations and improvements herein shown and described; the same being realized and attained through the instrumentalities and combinations pointed out in the appended claims.

The accompanying drawings referred to herein, and constituting a part hereof, illustrate one embodiment of the invention, and together with the description serve to illustrate the principles thereof.

Of the drawings:

Figure 1 is a fragmentary top plan of a machine embodying the invention;

Fig. 2 is an enlarged fragmentary vertical section on line A—B of Figs. 1 and 5;

Fig. 3 is a fragmentary elevation looking at Fig. 2 from the left;

Fig. 4 is a flat development, taken in section through the arc of the stop pins and coöperating mechanism, shown in Fig. 3;

Fig. 5 is an elevation and section, substantially on the line C—D in Fig. 1;

Fig. 6 is an elevation and section, substantially on the line E—F in Fig. 1, with certain parts omitted for the sake of clearness; and

Fig. 7 is a fragmentary elevation, with

parts in fragmentary section, looking at the distance determining device in Fig. 1 from the left, and showing certain parts of Fig. 6 in more detail.

In the illustrated embodiment, the invention is shown applied to and coöperating with a machine substantially similar to that shown in the Hawthorne Patent No. 1,241,258 already referred to. For clearness and brevity of explanation, certain parts of such a machine which are shown both in this application and in said Patent No. 1,241,258 will have the reference numeral which is applied thereto in the patent appended in parentheses after the reference numeral applied thereto in the present application.

The shape α (α) is impelled forward against a head 1 (26), mounted on a carriage 2 (25), which carriage slides along a guide way 3 (15) extending along the path of travel of the work α . Likewise extending along the path of travel of the work is the screw shaft 4 (40) and the latch 5 (46), which is operated and controlled by the solenoid 6 (54) and is adapted at the proper time, in accordance with the desired travel or distance of feed of the work, to engage with the screw shaft 4 (40), the two moving in engagement and coöperation to complete the desired or measured travel of the work. The energized foot, or other unit, bar 7 (60) acts to energize the solenoid and the trolley wires 8 (64) (116) (134) complete or return the various circuits.

The shaft 10 (75) is a continuation of shaft 4 (40), and they are rotated through a friction clutch 11 (76) and a gear train 12, 13 (78, 79) from a motor 14 (80).

The distance determining device, indicated generally by 15, 16 (89, 86) is connected to shafts 4 (40) and 10 (75) through a gear 17 (82) and a pinion 18 (81). The distance determining device, or that part herein shown, controls the rotation of the screw shaft to effect the feed of the work for inches and fractions thereof, the feed in feet being determined by the engagement of latch 5 (46) with the screw shaft 4 (40), as fully described in said Patent No. 1,241,258.

In the present embodiment, pinion 18 is sleeved on shaft 10 and is integral with or fixed to a clutch member 22, likewise sleeved on the shaft. A coöperating clutch member 23 is mounted to rotate with the shaft 10.

but is slidable therealong to engage and disengage 22, in a well-known manner. The operation of clutch 22, 23 is effected and controlled by a mechanism indicated generally 5 by reference numeral 24, which mechanism is shown and described in the application of George G. Frelinghuysen, Ser. No. 216,510 filed coincidently herewith. (Patent No. 1,331,493, issued February 24, 1920.)

10 One feature of the present invention relates to means for controlling the disks which, in the present embodiment, are permitted to rotate proportionately to the inches and sixteenths thereof over an integral foot required in the particular measurement or travel of the work which is being made.

15 Said means as embodied comprises co-operating devices whereby the screw shaft is returned to zero when a distance reading or setting extends beyond the next integral foot from the last previous reading; and, when the next distance reading or setting is beyond the next inch but is in the same integral foot, for permitting the inch pins and the sixteenths-of-an-inch slotted disk to return to zero under the impulsion of the gravity, or other automatic pressure device; and also, when the next succeeding distance 20 setting or reading is in the same inch, for preventing the restoration of the inch disk to the zero point.

25 The term "zero" herein is merely conveniently employed for any initial or basic point, and the term "restoring" is conveniently employed for bringing the rotating disks or equivalent distance determining devices into basic or standard relationship therewith.

30 40 The details of construction and operation of the inch and fractions of an inch part of the distance determining mechanism are clearly set forth in said Hawthorne Patent No. 1,241,258, and need not be repeated herein. It may be stated briefly that the plate 30 (89), mounted in fixed position on the machine frame, carries the solenoid operated pins 31 (101) which are automatically settable for the sixteenths-of-an-inch in the 35 desired distance reading. The rotatable disk 32 (88) has the slots 33 (100) therein, which are positioned and proportioned, when the corresponding pin is set, to give any desired feed up to fifteen-sixteenths-of-an-inch.

35 45 The disk 32 (88) has fixed thereto a sleeve 34 (87) mounted on shaft 35 (83). Fixed to sleeve 34 is a disk 36 (86) in which are mounted the solenoid operated inch pins 37 (91). Coöoperating with pins 37 (91) is the gear wheel 17 (82) which is meshed with pinion 18 (81), the distance determining device being thus connected to control the rotation of shaft 4 (40) to effect the desired feed 50 or travel of the work x , the disks traveling

proportionately to the work, under the control of the distance determining device, which in the present embodiment controls the setting of the inch pins and the sixteenths pins.

70 75 In the side of gear wheel 17 which faces disk 36 (86) with its pins 37 (91) in a slot 39 (90), into which slot a selected pin 37 (91) is automatically set or projected by a suitable distance record device, the so set pin engaging the end of the slot to stop the gear wheel 17 after the desired distance of travel of the work, the disk 36 and gear wheel 17 then traveling together so far as permitted by the set "sixteenths" pin 31, to 80 give or permit the desired or set distance of travel of the work beyond the last integral inch of the distance.

85 Referring now more particularly to Fig. 4, which is a flat development on an arcuate section through the center of the slot in Fig. 3 with the pins shown in full, the gear wheel 17 between the ends of slot 39 forms an abutment or stop for the inch pins 37. In the bottom of the slot 39 there are holes 90 40 spaced one inch apart of smaller size or diameter than the pins 37.

95 One of the pins 37, as for instance the eleven inch pin, is provided at its end with a projection 41 adapted to enter any one of the holes 40 which may be in register therewith. One of these holes will always be in register therewith at any inch setting, as the pins 37 are an inch apart and the holes 40 are also an inch apart.

100 The projection 41 is preferably conical in form, the holes 40 being correspondingly shaped, to permit easy release of the pin from the hole.

105 The inch pin carrying the projection 41 is connected in circuit so that when the pin y , which is any one of the inch pins, strikes the end of slot 39, as shown in Fig. 4, and it is desired to hold the disk 36 on the same inch, inch-pin w is projected into hole v of 110 the holes 40 before the new setting is made. Pin Y is then retracted and reset in the new reading and again catches the end of the slot as shown in Fig. 4, which has not been permitted to move owing to pin w being in hole v . Pin w is then deenergized and retracted, and gear 17 and disk 36 together will rotate for the fraction of an inch called for by the new setting of the sixteenths-of-an-inch pin which has been made in the new 115 inch. The pin w of the inch pins may be the one which holds disk 36 at an initial or zero position and is thus adapted to carry the projection 41 without otherwise interfering with the operation of the mechanism. 120

125 In accordance with one feature of the present invention, means are provided for effecting a feed of the work x for a sub-multiple of the ultimate fractional feed of the general mechanism. As embodied, this 130

is a feed for a thirty-second of an inch, which is half the distance between two adjacent settings of the disk.

As embodied, the plate 30 is not a fixed carrier or bearing for the sixteenths-of-an-inch pins, but the part 45 thereof (Figs. 6 and 7) is circular in form and is carried within a ring 46, which ring is fixed relatively to and carried upon the frame 47 of the machine. This disk 45 carries the sixteenths-of-an-inch pins, in this respect being the same as the plate 30 previously described, but disk 45 is movable within ring 46.

15 Mounted on ring 46 is a solenoid 48, the core 49 thereof having a pin 50 attached thereto. The pin 50 works in an aperture 51 in the ring 46 and is impelled by its spring 58 to project into a recess 52 in the disk 45. This holds disk 45 fixed in ring 46 during measurements terminating in an even inch or in sixteenths-of-an-inch.

In the periphery of disk 45 is a second aperture 54, having a dimension in the periphery of disk 45 permitting a thirty-second of an inch of feed of the work x . Into the aperture 54 projects a pin 55 fixed in the ring 46. When solenoid 48 is energized, it retracts pin 50 and disk 45 is permitted to 25 rotate the equivalent of a thirty-second of an inch of travel of the work. Thus, whenever it is desired to add a thirty-second to any distance reading or distance of travel of the work, the solenoid 48 is energized, 35 preferably from the distance record device, and retracts pin 50 against its spring and permits rotation of disk 45 until pin 55 strikes the opposite side of aperture 54. The disk 45 is restored by the automatic 40 pressure device (shown in Fig. 7 as a spring 56), and the solenoid 48 having been de-energized, pin 50 again enters aperture 52 under the impulsion of spring 58. Weight 57 acts to restore the entire disk mechanism 45 to initial position, the spring 60 in Fig. 4 corresponding to the weight 57.

It will be understood that the references to the foot and inch system of measurements, and likewise to the sub-multiple or fractions, sixteenths and thirty-seconds, is illustrative 50 merely and not restrictive of the invention.

In the embodied form of control by a distance record device, that is a sheet or other device in which has been punched or marked the position relatively to the beam of the holes to be punched and the distances between them (Fig. 1), contact points 61, 62 and 63 are energized from a source of electric energy 64, and make electrical contact, 55 through perforations 65 in a distance record sheet 66, with opposed contacts 67, 68 and 69, which in turn connect in circuit with contactor coils 70, 71 and 72. The opposite ends of these coils are connected to a negative line 73. The contactor coils when 60

ergized serve to close their respective contactors, 74, 75 and 76. Contactor 74, when closed energizes the solenoid coil which sets the stop pin 31 for the particular selected or desired sixteenth-of-an-inch of travel. Contactor 75 likewise acts to set stop pin 37 for the particular selected or desired inch of travel. Contactor 76, when closed, opens the circuit of the solenoid coil of stop pin 50, thereby releasing this pin and allowing the 75 mechanism to advance through the desired additional thirty-second of an inch, if such a measurement or advance is required.

The invention in its broader aspects is not limited to the details of construction shown 80 and described, but changes may be made therefrom, without departing from the principles of the invention and without sacrificing its chief advantages.

What I claim as my invention is:— 85

1. A distance determining device controlling the feed of the work in a metal working machine and including in combination a plurality of members moving proportionately to the travel of the work, settable devices coöperating with said proportionately moving members, and means for holding a proportionately moving member during a resetting of the settable means.

2. A distance determining device controlling the feed of the work in a metal working machine and including in combination a plurality of members moving proportionately to the travel of the work, settable devices coöperating with said proportionately moving members, means acting to restore said proportionately moving means between successive settings of said settable means, and means for holding a proportionately moving member during a resetting of the settable means. 95

3. A distance determining device controlling the feed of the work in a metal working machine and including in combination members moving proportionately to the travel 100 of the work and representing different distance denominations or submultiples, settable means coöperating therewith and representing distance values in the denomination and submultiple, and means for maintaining the position of one of said proportionately moving members while a new setting of the settable means is made for the other proportionately moving device. 110

4. A distance determining device controlling the feed of the work in a metal working machine including in combination members moving proportionately to the travel of the work and representing different distance denominations or submultiples, settable means coöperating therewith and representing distance values in the denomination and submultiple, and means for maintaining the position of the denomination 115 representing movable member while a re- 120

- setting of the settable means is made for the movable member representing the sub-multiple.
5. A distance determining device controlling the feed of the work in a metal working machine including in combination a plurality of plates traveling proportionately to the work, a plurality of settable pins engaging therewith, means for setting the pins, and means for holding the plates while a pin is retracted and reset.
6. A distance determining device controlling the feed of the work in a metal working machine including in combination a plurality of plates traveling proportionately to the work, representing distance denominations and representing distance values in denominations and a plurality of settable pins engaging therewith, means for setting the pins, and means for holding the plates while a pin is retracted and reset.
7. A distance determining device controlling the feed of the work in a metal working machine including in combination a plurality of rotatable disks moving proportionately to the work, a plurality of settable pins engaging therewith, means for setting the pins, and means for holding the disks while a pin is retracted and reset.
8. A distance determining device controlling the feed of the work in a metal working machine including in combination a plurality of rotatable disks moving proportionately to the work, representing distance denominations and representing distance values in denominations and a plurality of settable pins engaging therewith, means for setting the pins, and means for holding the disks while a pin is retracted and reset.
9. A distance determining device controlling the feed of the work in a metal working machine including in combination a mechanism settable to effect a desired travel of the work, and a device for effecting a travel of the work through a sub-multiple of the ultimate division distance of said mechanism.
10. A distance determining device controlling the feed of the work in a metal working machine including in combination a plurality of plates traveling relatively to the work, a plurality of settable pins engaging therewith to control the travel of the work, and a supplementary device permitting further travel of the work.
11. A distance determining device controlling the feed of the work in a metal working machine including in combination a plurality of plates representing distance denominations and traveling relatively to the work, a plurality of settable pins representing values in a distance denomination and engaging therewith to control the travel of the work, and a supplementary device permitting further travel of the work.
12. A distance determining device controlling the feed of the work in a metal working machine including in combination a plurality of rotating disks traveling relatively to the work, a plurality of settable pins engaging therewith to control the travel of the work, and a supplementary device permitting further travel of the work.
13. A distance determining device controlling the feed of the work in a metal working machine including in combination a plurality of relatively movable plates representing distance denominations traveling relatively to the work, a plurality of settable pins representing values in a distance denomination and engaging therewith to control the travel of the work, and a supplementary device permitting further travel of the work.
14. A distance determining device controlling the feed of the work in a metal working machine and including in combination a plurality of plates traveling relatively to the work, a plurality of settable pins engaging therewith to control the travel of the work, and a supplementary device permitting further travel of the work, the foregoing operating under the control of a distance record device.
15. A distance determining device controlling the feed of the work in a metal working machine and including in combination a plurality of plates representing different distance denominations and traveling relatively to the work, a plurality of settable pins representing values in a distance denomination or sub-multiples thereof and engaging therewith to control the travel of the work, and a supplementary device permitting further travel of the work, the foregoing operating under the control of a distance record device.
16. A distance determining device controlling the feed of the work in a metal working machine and including in combination a plurality of rotating disks representing distance denominations and traveling relatively to the work, a plurality of settable pins representing values in a distance denomination and engaging therewith to control the travel of the work, and a supplementary device permitting further travel of the work, the foregoing operating under the control of a distance record device.
17. A distance determining device controlling the feed of the work in a metal working machine and including in combination a plurality of members moving proportionately to the travel of the work, settable devices cooperating with said proportionately moving members, and means for holding a proportionately moving member during a resetting of the settable means, the foregoing operating under the control of a distance record device.

18. A distance determining device controlling the feed of the work in a metal working machine and including in combination a plurality of members moving proportionately to the travel of the work, settable devices coöoperating with said proportionately moving members, means acting to restore said proportionately moving means between successive settings of said settable means, and means for holding a proportionately moving member during a resetting of the settable means, the foregoing operating under the control of a distance record device.

19. A distance determining device controlling the feed of the work in a metal working machine and including in combination members moving proportionately to the travel of the work and representing different distance denominations or submultiples, settable means coöperating therewith and representing distance values in the denomination and submultiples, and means for maintaining the position of one of said proportionately moving members while a new setting of the settable means is made for the

other proportionately moving device, the foregoing operating under the control of a distance record device.

20. A distance determining device controlling the feed of the work in a metal working machine and including in combination members moving proportionately to the travel of the work and representing different distance denominations or submultiples, settable means coöperating therewith and representing distance values in the denomination and submultiple, and means for maintaining the position of the denomination representing movable member while a resetting of the settable means is made for the movable member representing the submultiple, the foregoing operating under the control of a distance record device.

In testimony whereof, I have signed my name to this specification, in the presence of two subscribing witnesses.

EDWARD V. WURTS.
